Filed Feb. 21, 1968, Ser. No. 10,674

Term of patent 3½ years

Int. Cl. D6—01

U.S. Cl. D33—19

FIG. 1 is a perspective view of a chest embodying my new design;

FIG. 2 is a front elevational view, the back of the chest being substantially the same in appearance;

FIG. 3 is a sectional view taken along lines 3—3 of FIG. 2 thereof, showing shape of the container portion to more clearly bring out my new design; and

FIG. 4 is a side elevational view taken from the left in FIG. 1.

I claim:

The ornamental design for a chest, substantially as shown and described.
